BUCKLE

James T. Duffy, Jr., Wynnewood, Pa., assignor to
Pioneer Suspender Company, a corporation of
Pennsylvania

Application June 29, 1933, Serial No. 678,178

7 Claims. (Cl. 24—178)

My invention relates to improvements in buckles, especially buckles for apparel belts.

The object is to provide an improved buckle frame, of comparatively soft or yielding material such as leather, with a rigid tongue member so formed as to provide a brace to prevent distortion of the frame when tension is exerted upon the same by the belt.

As is well known in the art, there has long been and there still is a considerable demand for belt buckles for personal wear, having an outer surface of leather. This demand has heretofore been supplied by covering a metallic buckle frame with leather. This construction is however quite expensive, and the attempt has been made to construct such buckle frame entirely of leather. This construction however has not been successful because of the yielding character of the leather, and when tension is exerted upon the frame, by the belt under tension, the frame is liable to become distorted, sometimes to such a degree as to permit the front portions of the frame to separate from the end of the tongue, so that the tongue will become disengaged from the belt end.

In accordance with the present invention the buckle frame is formed entirely of leather, suitably shaped and provided with a metallic tongue, the free end of which is provided with a hook which engages the front middle portion of the leather frame and prevents said portion or extension from being distorted or pulled out of its normal contour.

Referring to the drawing which illustrates merely by way of example, a preferred embodiment of the invention;

Fig. 1 is a plan view.

Fig. 2 is a plan view of the buckle end of the belt on an enlarged scale with part broken away.

Fig. 3 is a side elevation of same with part broken away.

Fig. 4 is an end elevation.

Similar numerals refer to similar parts in the several views.

The frame 5, in the present example, is made of a strip of leather, preferably to match the strap portion 6 of the belt, rolled into a circular cross-section, with the meeting longitudinal edges stitched together as at 7. The rear ends of the frame-forming strip are flattened out and secured, preferably by stitching between layers of the belt strap 6. A pin or shaft 8 of metal is enclosed within the folded portion of the belt, to which the frame is secured, and forms a bearing

or shaft for the tongue 9, which is also of rigid metal.

When the free end of the belt, having the holes for engagement with the tongue, is under tension, the tendency is for the belt to slip toward the free end of the tongue. This tendency is normally counteracted by the engagement of the belt with the front portion of the frame. If the arched front portion 10 of the frame is sufficiently yielding it may become distorted by the pull of the belt strap, even to such extent as to become disengaged from the front or free end 11 of the tongue, whereupon, of course the free end of the belt becomes disengaged from the tongue.

By shaping the free end of the tongue into the form of a hook 12, fitting the cross-sectional contour of the frame, the said arch extension 10 of the frame is clamped securely against said distortion or outward movement so that the distorting action by the pull of the belt upon the adjacent parts of the frame flanking the hook is entirely prevented. It follows that by this arrangement a frame constructed of quite flexible or yielding material, will be held with sufficient rigidity by the clamping action of the tongue hook to form an extremely serviceable buckle construction.

In other words the invention comprises a buckle frame of material so soft or yielding that it is incapable of resisting the distorting action of the normal pull of the belt when worn with the usual tension, and a cooperating buckle tongue having a hook formation for engaging the front or arched portion of the belt to prevent such distortion.

What I claim is:—

1. A buckle having in combination, a frame formed of yielding material such as would be distorted by the pull of the belt under normal wearing conditions, and a rigid tongue having a hook at its free end corresponding with the cross-sectional contour of the front portion of the frame adapted to fit thereon and clamp said front portion or extension to prevent its outward movement or distortion from its normal contour.

2. A buckle having in combination, a frame formed of yielding material such as would be distorted by the pull of the belt under normal wearing conditions, a rigid bearing pin and a rigid tongue journaled thereon, said tongue having a hook at its free end corresponding with the cross-sectional contour of the front portion of the frame adapted to fit thereon and clamp said front portion or extension to prevent its

outward movement or distortion from its normal contour.

3. A belt buckle comprising a frame of yielding, flexible material such as would be distorted 5 by the pull of the belt under normal wearing conditions, the rear ends of which are adapted to be secured to the belt, a pivotally mounted rigid tongue associated with said frame having its free end bent to correspond to the cross- 10 sectional contour of the front portion of the frame and adapted to cooperate therewith to prevent distortion of the frame.

4. A belt-buckle, comprising a frame of yielding material such as would be distorted by the pull of 15 the belt under normal wearing conditions, having rear ends secured to the belt, a pivot associated therewith, a rigid tongue mounted on the pivot and having its free end bent to correspond to the cross-sectional contour of the front portion of the 20 frame for cooperation therewith to prevent distortion of said frame.

5. A belt-buckle, comprising a frame made of a strip of leather, rolled into circular cross-section, with the meeting longitudinal edges secured to-

gether, a rigid pivoted tongue associated therewith, said tongue having a hook formation at its free end adapted to cooperate with the front portion of the frame to prevent distortion.

6. A belt-buckle, comprising a frame made of a strip of leather, rolled into circular cross- 5 section, with the meeting longitudinal edges secured together, except the rear ends, which are maintained flat for securing the same to the belt, a rigid pivoted tongue associated therewith, said 10 tongue having a hook formation at its free end adapted to cooperate with the front portion of the frame to prevent distortion.

7. A belt-buckle, comprising a frame made of a strip of leather, rolled into circular cross- 15 section, with the meeting longitudinal edges secured together, except the rear ends, which are maintained flat for securing the same to the belt, a pivot associated with said frame and belt, and a rigid tongue mounted on said pivot and pro- 20 vided with a hook formation at its free end for cooperation with the front portion of the frame to prevent distortion.
